UNITED STATES PATENT OFFICE

AUGUST LUECKEL, OF BROOKLYN, NEW YORK.

PICTURE-EXHIBITOR.

SPECIFICATION forming part of Letters Patent No. 253,730, dated February 14, 1882.

Application filed October 26, 1881. (No model.)

To all whom it may concern:

Be it known that I, AUGUST LUECKEL, of Brooklyn, in the county of Kings and State of New York, have invented a certain new and 5 useful Improvement in Picture-Exhibitors, of which the following is a full, clear, and exact description.

My invention relates to ornamented cards, generally termed "Christmas" and "birthday" 10 cards, and has the object to obtain a greater variety and more ornamental effect than are furnished by the cards as usually made.

The invention consists in the combination of a folding card with a supporting-frame or easel, 15 as hereinafter described and claimed.

Reference is to be had to the accompanying drawings, forming a part of this specification, in which similar letters of reference indicate corresponding parts in all the figures.

20 Figure 1 is a perspective view of my folding card in an open position. Fig. 2 is a horizontal section of the same in a partially-folded position, and Fig. 3 is a vertical section of card as folded.

25 A is the supporting-frame or easel, consisting of a sheet, *a*, of card-board, having a portion cut out to form a supporting-leg, *b*, by which the frame is held at a proper inclination.

The folding card consists of a main portion, 30 *c*, that is attached to the card-board *a*, and the leaf portions *d d*, that are attached by a flexible connection, *e*, so that they can be folded down upon the main portion *c* or opened out, as illustrated in Fig. 1.

On the face of the card *c* a picture or other 35 ornamental design is printed, and both sides of the hinged portions *d* are similarly ornamented, so that five separate pictures or ornamented surfaces are given.

Around the edges of the card *c* is a border- 40 *f*, of ruffed or plain material, and fringe is added as a finish.

The cards mounted and arranged in this manner are highly ornamental, and are displayed to the best advantage by the supporting-frame. 45

The folding portions may be differently arranged. For instance, they may be attached to fold up or down instead of sidewise, and a single leaf used in place of two.

I am aware that it is not new to make a case 50 with leaves hinged to a central stem for the display of photographic cards, or one with a hinged back, folding side, top, and bottom, as well as with flaps, like those of a letter, closing over the picture; but

55 What I claim as new is—

A picture-exhibitor consisting of the sheet *a*, with cut-out leg *b*, the folding card *c*, attached to sheet *a*, and the leaves *d*, flexibly connected with card *c*, whereby several ornamental designs or pictures may be shown, as described.

AUGUST LUECKEL.
